SHAVING IMPLEMENT

Joseph Muros, Cambridge, Mass., assignor to
 Gillette Safety Razor Company, Boston, Mass.,
 a corporation of Delaware

Application October 23, 1936, Serial No. 107,233

16 Claims.

(Cl. 30—43)

This invention relates to implements of general application to the shearing, trimming or cutting of sheet material or filamentous material. One important field of use of the invention is in implements for shaving without the use of lather and for purposes of illustration it will be described in that connection.

In one aspect the invention consists in co-operating members presenting curved shearing edges and contacting in spherical guiding or bearing surfaces, together with means for moving one member with respect to the other to impart a progressive circular shearing movement to its edge or to the two co-operating edges. The two members may be so shaped and related as to present a crescent-shaped opening between their circular shearing edges of any desired amplitude. Where the implement is used for shaving and is intended for cutting hair an opening of perhaps .015" is entirely adequate, although where the implement is designed for cutting sheet material under conditions which are safe for the user a much wider opening may be desired and is entirely practicable.

One desirable manner of bringing about a progressive circular shearing movement of the implement is to move a portion of the inner member in a circular path which may be concentric with respect to the axis of the member. Under these circumstances the portion of the inner member presenting the movable shearing edge partakes of a wobbling motion, closing the opening at one end and progressively opening it at the other in a circumferential direction about the contour of the stationary shearing edge. Accordingly, hairs which are introduced into the opening as the implement is moved over the face of the user are progressively sheared. The implement is designed to be driven at high speed and consequently to engage and shear all the hairs on the face of the user as the implement is moved across it.

As herein shown the two members are yieldingly maintained in engagement at their spherical guiding surfaces and the friction thus developed is sufficient to prevent the inner member from spinning freely about its own axis, as might be the case if the guiding friction and the friction of the driving connection were approximately equal. Where the guiding friction of the spherical surfaces exceeds the friction of the driving connection it has been found that the inner member will partake of a slow rotational movement in addition to its wobbling movement when the implement is running idly.

This is advantageous in that the point of engagement of the two shearing surfaces is thus progressively changed and a progressive self-sharpening action at two points in the circular shearing edge is brought about. Thus the efficiency and effective life of the implement are prolonged with great advantage to the user.

Implements may be constructed in accordance with the present invention having shearing members arranged either externally or internally with respect to each other. In my co-pending application, Serial Number 104,967, filed October 10, 1936, I have disclosed an implement having shearing members arranged one within the other and have made in that application claims generic to both forms of implements. The present application is accordingly restricted to implements in which one shearing member is arranged externally with respect to the other, although such construction comes within the scope of many of the claims of my co-pending application above identified. Each form of implement has its own usage and characteristics. In the internal arrangement the shearing cut takes place in the upward or outward direction, that is to say, the shearing edge of the inner member moves outwardly to meet the shearing edge of the outer member and the shearing edge of the outer member constitutes also a guide and gauge surface for the implement in its movement on the face of the user. On the other hand, in an externally organized implement the shearing cut takes place in downward or inward direction as the shearing edge of the inner member is moved downwardly to meet and co-operate with the stationary circular edge of the outer member. Moreover, since the outer member extends beyond or without the plane of the stationary cutting edge it may be utilized as a guide or guard surface. As embodied in a shaving implement it may be shaped to operate with a massaging effect.

These and other features of the invention will be best understood and appreciated from the following description of several preferred embodiments thereof, selected for purposes of illustration and shown in the accompanying drawings, in which:—

Fig. 1 is an end view on an enlarged scale of a dry shaving implement;

Fig. 2 is a similar view in side elevation, a portion of the casing being shown as broken away;

Fig. 3 is a similar view in front elevation;

Fig. 4 is a similar view in longitudinal section;

Fig. 5 is a view in elevation of the inner shear

member, with its path of movement indicated in dotted lines;

Fig. 6 is a plan view of the shearing members of a modified shaving implement on a still larger 5 scale;

Fig. 7 is a fragmentary view, partly in section and partly in elevation of the implement shown in Fig. 6;

Figs. 8 and 9 are corresponding views of still 10 another embodiment of the invention in a shaving implement; and

Fig. 10 is a fragmentary view in elevation of the parts shown in Figs. 6 and 7.

The implement includes in its structure a casing 10, of which only a portion is shown in Figs. 15 2, 3, and 4, and which may serve as a handle for the implement and as a housing for the motor actuating it. In the upper end of the casing 10 is removably secured, by a clamping screw 12, a 20 rectangular metallic head 11 upon which the operative parts of the implement are mounted. The head 11 is provided with an upstanding circular boss 13 threaded upon its outer surface. Upon this is screwed a casing 14 having a cylindrical 25 internally threaded portion and upper portion 16 having a spherical inner wall tapering to a circular shearing edge 17. The cylindrical portion 14 of the casing is provided with a series of perforations 15 for the purpose of ventilation and to permit 30 the ready discharge of debris sheared by the implement.

The inner member comprises a hollow spherical body portion 20 having a guiding surface which coincides with the inner spherical guiding surface 35 of the casing 14 and connected through a perforated web 21 with a downwardly extending central stem 22. The stem 22 is provided with an end recess 23 for driving connection with a spherical stud 29 which projects eccentrically from the 40 upper end of the motor shaft 28. In Fig. 4 the driving stud 29 is shown as in its extreme left-hand position, that is to say, displaced about one-sixteenth of an inch from the axis of the motor shaft 28. The inner member extends above the 45 web 21 and terminates in a flattened circular head 25 spaced from the web 21 by a circumferential groove 24. The circular marginal surface of the head 25 is spherical and concentric with the spherical guiding surfaces of the two shearing members, the center of curvature of these surfaces 50 being indicated in Fig. 4 as somewhat nearer the lower end of the stem 22 than the surface of the head 25.

The co-operating shearing members are held 55 in continuous yielding engagement by means of a compression spring 27 which is seated at its lower end in a concentric groove in the face of the boss 13 and bears at its upper end against the web 21. It will be seen, therefore, that the 60 spring 27 maintains the two members under continuous yielding pressure and consequently develops an appreciable amount of surface friction between the two spherical guiding surfaces.

The rotation of the eccentric stud 29 about the 65 axis of the shaft 28 imparts to the lower end of the stem 22 a circular motion in a path concentric with the axis of the motor shaft and having a diameter of twice the eccentricity of the head 29, as indicated in dot and dash lines in Fig. 4. 70 The co-operating shearing members are so designed that when the eccentric stud 29 occupies a position at one extremity of its path the head 25 is rocked or tilted to position its shearing edge 26 with an appreciable space between it and 75 the stationary circular shearing edge 17 of the

outer member. At its corresponding edge, that is to say, at its left-hand edge as shown in Figs. 1, 3, and 4, the opening between the two shearing edges extends convergently in both directions from this point of maximum opening and so presents a crescent-shaped space which is adapted to receive the material to be sheared. At the point opposite the maximum opening, that is to say, at the extreme right-hand side of the head 25, as shown in Fig. 4, the edge of the head is 10 carried below circular shearing edge 17 of the outer member to a point of maximum depth. As the eccentric head 29 is rotated a combined rocking and rolling or wobbling movement is transmitted to the inner shearing member with the 15 result that the opening between the two shearing edges is moved rapidly in a circular path about the implement, continually closing at one end and continually opening at the other.

It is contemplated that the motor shaft 28 will 20 be driven at a relatively high speed, for example, at least 3600 R. P. M. Consequently, as the implement is moved across the face of the user the passage of the shearing opening is so rapid that all hairs are given an opportunity to enter it and 25 are sheared before they have time to be withdrawn.

As already intimated Fig. 5 indicates the two extreme positions occupied by the inner shearing member in its cycle of movement. It will be 30 understood that these positions are not arrived at by a simple rocking movement but are the result of a combined rocking and circular movement. The slow spinning movement above referred to takes place without or independently 35 of bodily displacement of the inner shearing member and is the result of combined slip between the eccentric head 29 and walls of the recess 23 in the stem 22 and a lesser amount of slip between the spherical guiding surface of the two 40 members.

The implement illustrated in Figs. 1 to 5 presents a continuous unguarded stationary shearing edge 17, whereas in the implement shown in Figs. 6, 7, and 10 the stationary shearing edge of the 45 outer member 30 is provided with inwardly projecting guard teeth 31 which defines a series of circular segmental shearing teeth 32. The construction of these figures is particularly useful as supplying an additional safeguard for the user and as permitting the implement to be adjusted 50 for a wider shearing opening with safety to the user than would otherwise be possible.

The modification shown in Figs. 8 and 9 departs from the construction already described 55 in that the inner shearing member 40 is provided with a circular series of perforations 41 instead of having a continuous circular shearing edge as in Figs. 5 and 7. In this modification the inner shearing member 40 has a spherical wall which 60 is co-extensive with the spherical wall of the outer member 16 but is somewhat flattened in its upper portion. The perforations 41 extend radially through the walls of the member 40 in a circular series so located that in open position as 65 shown in Figs. 8 and 9 they are fully exposed above stationary shearing edge of the outer member and are thus positioned to receive the hairs to be cut. In the wobbling movement of the inner shearing member the perforations 41 are 70 carried below the stationary shearing edge 17 and the upper edge of each perforation therefor as a shearing edge in co-operation with the stationary edge 17.

Provision for adjustment of the amplitude of 75

the shearing opening is available by screwing the outer member 16 in or out upon the threaded boss 13. In this movement of the member the effective point of connection between the eccentric head or stud 29 and the stem 22 of the inner member is moved with respect to the axis of movement, viz., the center of curvature of the spherical guiding surfaces. Accordingly, the shearing opening is increased or diminished in 10 amplitude. This adjusting feature, of course is not limited to an implement in which one shearing member is located externally with respect to the other but is of general application to all implements of the rotary shearing type.

15. The marginal surface of the head 25 is spherical in shape and of a radius of curvature corresponding to that of the annular spherical surface of the outer member 16 or 30, while the upper or end surface of the head is appreciably flattened and of a substantially longer radius of curvature. The result is that in the movement 20 of the head about its center of curvature as an axis the flattened end surface of the head is angularly displaced and thus imparts a vibratory 25 massaging effect to the face of the user. The same effect is secured from the implement shown in Figs. 8 and 9 wherein the upper or endmost surface of the inner member 40 is flattened so 30 that it is not concentric with the radius of curvature of the spherical guiding surface of the two members.

Having thus described my invention, but without limiting it to the mechanical details illustrated, I claim as new and desire to secure by 35 Letters Patent:—

1. An implement of the class described having co-operating members presenting shearing edges and spherical guiding surfaces, and means for 40 imparting a wobbling movement to one of said members to move its edge externally and progressively with respect to the edge of the other member.

2. An implement of the class described having 45 co-operating members, one arranged externally with respect to the other and both presenting shearing edges and spherical guiding surfaces, and means for imparting a circular movement to a portion of one of said members.

3. An implement of the class described having 50 co-operating members, one arranged externally with respect to the other and both presenting shearing edges and spherical guiding surfaces, and means for imparting a wobbling movement to the external edge-bearing portion of one member.

4. An implement of the class described having 55 co-operating members one arranged externally with respect to the other, said members presenting circular shearing edges and having inter-related spherical guiding surfaces, together with a crescent-shaped shearing opening and for moving one member with respect to the other to cause 60 said opening to travel circumferentially.

5. An implement of the class described having 65 an outer stationary member presenting a circular shearing edge which lies in a predetermined plane, a movable inner member presenting a co-operating shearing edge which lies in a plane partly external to the shearing edge of said outer member, and means for rocking and turning 70 said inner member.

6. An implement of the class described having 75 a hollow member presenting a circular shearing

edge, an inner member movably mounted with said hollow member and having a head external thereto which presents a circular shearing edge, and means for moving said inner member to effect a progressive shearing action.

7. An implement of the class described having a hollow member presenting an annular shearing edge, an inner member having a convex face bounded by a circular shearing edge, and mechanism for imparting an inwardly-shearing wobbling movement to said members.

8. An implement of the class described having a hollow member presenting an annular shearing edge and having a spherical seat formed directly in its inner wall, an inner member having a 15 spherical surface received in said seat, and a head disposed partly above the annular shearing edge of said hollow member and presenting a circular shearing edge, and mechanism for 20 rocking and turning said inner member on its seat to impart an inwardly-shearing movement to its edge.

9. An implement of the class described having an outer member presenting an overhanging circular shearing edge and having an internal spherical seat, an inner member positioned upon said seat and having a convex head which projects partially through the circular shearing edge of said outer member and is bounded by a circular shearing edge, and mechanism for turning 30 and rocking said member upon its seat.

10. An implement of the class described having an outer member presenting a circular shearing edge, an inner member also presenting a circular shearing edge and having a spherical bearing seat with a center of curvature internal in the implement, and mechanism for rocking and turning said inner member upon its seat.

11. A shaving and massaging implement having 35 co-operating spherical surfaced members with complementary circular shearing edges, one of said members presenting a convex head, and means for wobbling said member about a center eccentric to the center of curvature of said 40 head.

12. An implement of the class described having 45 co-operating spherical surfaced members with complementary circular shearing edges located always in angular relation with a shearing opening between them, and means for adjusting the amplitude of said opening.

13. An implement of the class described having 50 co-operating members having spherical guide faces and complementary circular shearing edges 55 located in angular relation with a crescent-shaped opening between them, means for relatively moving said members to advance said opening circumferentially of the implement, and means for relatively adjusting the members to 60 regulate the amplitude of said opening.

14. An implement of the class described having 65 co-operating spherical-surfaced members with complementary circular shearing edges, a frame having driving mechanism therein connected to one of said members, and provision for adjusting said members with respect to said frame without interrupting the connection with said driving mechanism.

15. An implement of the class described having 70 co-operating spherical-surfaced members with complementary circular shearing edges, spaced guard teeth associated with one of said edges, and means for relatively moving said members 75

to impart a progressive shearing action to their edges.

16. An implement of the class described having co-operating spherical-surfaced members with complementary shearing edges, those of one member being formed by a plurality of perfora-

tions, and means for wobbling one member with respect to the other upon their spherical surfaces to cause shearing action at one after another of said perforations.

JOSEPH MUROS. 5
